UNITED STATES PATENT OFFICE.

CHARLES MERGNER, JR., OF NEW YORK, N. Y.

DESIGN FOR A PATRIOTIC BADGE OR POSTER.

53,928.

Specification for Design.

Patented Oct. 7, 1919.

Application filed January 11, 1918. Serial No. 211,440. Term of patent 3½ years.

To all whom it may concern:

Be it known that I, CHARLES MERGNER, Jr., a citizen of the United States, residing at Bronx, New York, in the county of New York and State of New York, have invented a new, original, and ornamental Design for a Patriotic Badge or Poster, of which the following is a specification, reference being had to the accompanying drawing, forming a part thereof.

The figure is a front elevation of a patriotic badge or poster, showing my new design.

I claim:

The ornamental design for a patriotic badge or poster, as shown.

CHARLES MERGNER, JR.
